UNITED STATES PATENT OFFICE.

MORTIMER G. PORTER, OF NEW BRITAIN, CONNECTICUT.

BOX-PULL.

SPECIFICATION forming part of Letters Patent No. 409,064, dated August 13, 1889.

Application filed April 29, 1889. Serial No. 309,073. (No model.)

To all whom it may concern:

Be it known that I, MORTIMER G. PORTER, a citizen of the United States, and a resident of New Britain, in the county of Hartford and State of Connecticut, have invented certain new and useful Improvements in Box-Pulls; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention as applied to a box and is a perspective view. Fig. 2 is a side view of the pull detached from the box; and Fig. 3 is a perspective view of a slightly-different position of the pull as applied to a box, the box being indicated by dotted lines.

In the accompanying drawings, A indicates a spiral formed at one end of a wire, and B a ring formed by bending the wire at the opposite end at a right angle to the said spiral. The spiral A consists of two whirls c c, which are designed to clasp the front wall C of a box between them when slipped over the edge of said front wall in the manner shown, the pull-ring B remaining on the outside of the front of the box and extending therefrom in position to be readily manipulated for the purpose of drawing the box from the shelf. The whirls c c of the spiral or clasp are of equal diameter and lie closely together one upon the other.

The spiral clasp A is attached to the front of the box by introducing the upper edge of said front between the whirls, whereby one whirl bears flatly against the inner side and the other whirl bears in a similar manner against the outer face of the said front, this outer whirl being continued or curved outward in a plane at right angles to said whirl to form the pull-ring. This box-pull is removable, and is designed more especially for boxes made of pasteboard or other thin material—such as shoe-boxes, shirt-boxes, and the like; but it is obvious that the strength of the pull may be increased by the use of heavier material to adapt it to boxes of greater size and weight. The pull is also adjustable, as the spiral clasp A has free play against the face and back of the box-front, so that the pulling-ring may be made to assume various positions by turning the clasp in the direction required.

What I claim, and desire to secure by Letters Patent, is—

A box-pull constructed of a single wire having at one end a spiral clasp and at the opposite end a ring at right angles to the plane of the clasp, substantially as specified.

In testimony whereof I affix my signature in presence of two witnesses.

MORTIMER G. PORTER.
